UNITED STATES PATENT OFFICE.

HENRY HIGGIN, OF NEWPORT, KENTUCKY, ASSIGNOR TO THE HIGGIN MANUFACTURING COMPANY, OF NEWPORT, KENTUCKY, A CORPORATION OF WEST VIRGINIA.

SPRING-PLATFORM FOR VEHICLE-SEATS, CHAIRS, LOUNGES, AND BED-BOTTOMS.

No. 867,507.

Specification of Letters Patent.

Patented Oct. 1, 1907.

Application filed November 19, 1904. Serial No. 233,520.

To all whom it may concern:

Be it known that I, HENRY HIGGIN, a citizen of the United States, and a resident of the city of Newport, in the county of Campbell and State of Kentucky, 5 have invented certain new and useful Improvements in the Spring-Platforms for Vehicle-Seats, Chairs, Lounges, and Bed-Bottoms, of which the following is a specification.

The several features of my invention and the various 10 advantages resulting from their use conjointly or otherwise will be apparent from the following description, and claims.

I will now proceed to describe my invention in detail.

15 In the accompanying drawings making a part of this application, and in which similar letters of reference indicate corresponding parts,—Figure 1 is a view in perspective of my invention applied to a chair. The upper covering of the seat, and a portion of the middle 20 or seat part of the chair are removed, so that my invention in its relation to the chair can be clearly seen. Fig. 2 is a top or plan view of my spring platform. Fig. 3 is a bottom view of this platform, viewed from below it. Fig. 4 is a view in perspective of the device for 25 directly supporting the bottom of the spring. Fig. 5 is a perspective view of the device for securing the upper part of the spring to the upper frame. Fig. 6 is a perspective view of this device of Fig. 5, and a part of a spring secured together according to my design. 30 Fig. 7, Sheet two, is a plan of the rod devices for securing at the top of the spring platform the springs together. Fig. 8 is a plan of a rod frame, employed in connection with the device shown in Fig. 4, to secure 35 together the springs at their lower ends, and at the bottom of the platform. Fig. 9 is a device, shown in perspective, for securing the rod frame of Fig. 8, to the lower frame of the platform, at the front and sides of the article. Fig. 10 are devices, viewed in perspective, of another form for connecting the basal spring 40 supports of Fig. 4 to the sides of the platform. Fig. 11 is a perspective view of devices for connecting the adjacent basal rod frames of Fig. 8 to the rear part of the platform, where extensions without springs are necessary. Fig. 12 represents, in perspective, a detail, 45 namely: that portion of a uniting frame which contains eyes for enabling this frame to be connected with other portions of the spring platform.

A indicates the lower frame of the spring platform. This frame is usually of wood and of considerable 50 strength. The upper frame B at or near the top of the platform is a metal rod. The springs C are of a conical spiral shape, are made of rod, their smallest end, or apex being below, and their largest part being at the top. This kind of spring is of itself old.

In constructing my platform, I provide a basal support or seat for each spring. This basal support E (see Fig. 4) has a depression or channel E², present at each end. One or more openings E³ in this depression formed by elevating the bottom of the depression at E⁵ serve to receive the lower end of the spring. The latter is passed through these openings E³ and held in position in the channel E². This is the preferred mode of securing it to this seat E. Each end of this seat E is bent around in the form of a roll E⁴. To connect these basal supports or seats E is the function of the rod frame D. This frame has the inclined sides D² and the flat sides at D⁵, D⁶, and these straight sides are respectively received into the adjacent rolls E⁴, E⁴ of two seats E, see Fig. 3. The ends D³ and D⁷ of these rod frames D are secured to the adjacent ends 70 of similar rod frames, substantially as shown. The rod frame has a straight end D⁷. The other end consists of the ends D³, D⁸ of the rod, and each of these ends is curved over, respectively forming similar hooks D⁴, D⁴, both turned the same way, and together 75 constituting one hook. This hook of one rod frame D engages the straight part D⁷ of the adjacent rod-frame D, see Fig. 3. In this manner, the said parts are interconnected. It is necessary to connect this bottom construction thus far described to the bottom frame A. 80 To effect this connection, I provide the device H for connecting the straight part D⁷ of a hook D⁴ to the frame. This part D⁷ is embraced in the hollow cylindrical or curved end H⁶ of the piece H. The piece H is 85 preferably provided with the extended portion H⁵ so as to drop the curved part H⁶ below the top of the frame, and allow the bottom part of the platform to be lower down. A part H² of the piece H is preferably present, being the preferred means for securing the piece to the frame. Bolts or screws or nails are in such case passed 90 through the holes H⁴ into the frame A.

To secure the basal supports or seats to the frame, I provide a device, see Fig. 10, consisting of a link F, suitably secured in an oscillatory manner to the seat E and to the frame A. A preferred kind of such connection is as follows: The plate G is bolted at G³ to the top of the frame A and in its hollow cylindrical or curved end G² is contained one side F³ of the link F, free to turn therein. The opposite side F² of this link is contained in the adjacent curved end E⁴ of 100 the seat E and is free to turn therein, see Fig. 3.

It is often desirable to leave some space between the spring platform and the rear part of the frame A. This is especially the case on large chairs where the back is upholstered and extends forward for a distance in front of the frame of the back of the chair. In such event, I provide a device for connecting the rear part of the platform to the rear part of the frame

A, or its equivalent. This device consists, see Fig. 11, of a connecting rod, preferably made as shown in Fig. 11, namely: the rod has a straight portion I³ and sides I², I⁴, which converge so that the ends I⁴, I⁴ meet 5 as shown and are each curved at I⁵. These curved ends I⁵, I⁵ constitute a single hook, which grasps a straight portion D⁷ of an adjacent rod frame D. The straight part I³ of the rod is pivotally connected to the frame preferably by a piece J, bolted, nailed or 10 screwed to the top of the frame at J², and having at its edge a hollow cylindrical or curved portion J³, which loosely embraces the straight part I³ of the rod I, and leaves the latter free to turn therein.

The construction of the upper portion of the spring 15 platform is substantially as follows:—I provide a rod frame K which is substantially like rod frame D, namely: having a straight end K³. The opposite end of the frame is provided with a hook. This hook preferably consists in making each free end K⁴, K⁴ of the 20 rod frame of a hooked form K⁵, K⁵. These hooks turn the same way and together form a single hook. Between the end K³ and the hook K⁵ on each side is a straight portion K⁶, and for the purpose of enabling each side to be readily attached to its adjacent spring, 25 the rod frame of the straight portion K⁶ is bent into the form of an eye, so that there is a straight portion K⁶ provided at each end with an eye portion K⁷. The upper rod of the adjacent spring is passed through these eyes K⁷, K⁷, and is thus held firmly in position. 30 This clamping device just described is efficient. The connection between these rod frames K and the spring beyond the ends K³, K⁴, K⁴ of the rod frame is preferably made by means of a device such as L. This connection consists of two rods L², L², each of the rods 35 at one end being provided with an eye L⁴, and such eye embraces an upper wire or rod of an adjacent spring. The other end of one set of these connections L² is provided with a hook L³. These hooks engage the straight part K³ of the rod frame K. Inasmuch 40 as the pieces K² of rod frame K converge toward the straight part K³, the hooks L³ will not slip laterally. The rods L², L² at the other end of the rod frame are preferably made integral at L⁵, and a hook there is omitted, a straight portion L⁵ being present where 45 the hooks would have been. The hooks K⁵, K⁵ of the rod frame K engage this straight portion L⁵. For a full understanding of these constructions, see Figs. 2 and 7.

The upper end of the spring C may be connected to 50 the upper frame B of the spring platform in various ways. The connection may be made by welding, or by a suitable device. The preferred form of device for uniting the upper end of the spring C to the upper frame B of the spring platform is as follows:—I provide 55 a hooked clip M, shown in Fig. 5, consisting in detail of the straight portion M², united to shoulders M³. These shoulders M³ are continued in the pieces M⁴, curving away from said shoulders; and the pieces M⁴ continue the curve and merge respectively into the 60 hooks M⁶. Before this device is applied, there is a space, see Fig. 5, between the straight portion M² and the free ends of the hooks M⁶ sufficient to admit successively the upper rod of the spring C and the rod of the upper frame B. When the clip is thus located around 65 these parts just mentioned, the hooks M⁶ are bent up-

ward and down at the sides of the straight portion M². The clip thus closed embraces the adjacent part of the spring C and the adjacent portion of the rod frame B as shown in Fig. 6.

Many of the parts of my invention have an advantage 70 resulting from their individual construction, and many of them have an advantage arising from their connection with other parts of the mechanism.

A great many slight changes might be made in the general form and arrangement of the parts described 75 without departing from my invention, and hence I do not confine myself to the precise details set forth, but consider myself at liberty to make such slight changes and alterations as fairly fall within the spirit and scope 80 of my invention.

The seat E is very rapidly manufactured and affords a thorough support for the spring. At the same time connection is quickly made with the adjacent rods. The part E thus constitutes not only a seat, but a link very convenient, very cheap of construction, easily 85 applied and effective in use. The rod frame D of Fig. 8 is very simple, easily constructed and very strong. The same is true of the rod frame K, and its eyes K⁷ afford a very valuable addition to this simple device, that although valuable in use are cheap of manufacture. The parts L², L², with their terminals as described are easy of manufacture and strong in use. The piece H provided with its hollow cylindrical part or sleeve H⁶ provides an attachment which is strong, 90 not readily disturbed and holds the rod frame securely 95 to the lower frame.

The device shown in Fig. 10 is a valuable link and is very convenient, connecting the seat E to the lower frame A. The rod frame I of Fig. 11 pivotally connected to the piece J and the hooks I⁵, I⁵, is simple, strong 100 and allows the platform an extended oscillation up and down. The entire platform when united substantially as shown is of great elasticity and remarkable strength. A man can stand upon one corner of this spring platform and jump up and down without deranging it, and after he steps off, it will resume its original position. In many cases, particularly in the seats of road and similar vehicles, the lower frame A, that in chairs is usually of wood, will preferably be of metal, and of a rod form. In such event, it will be 110 usually desirable to omit the links and have the metal rod frame engage directly one of the curved ends E⁴ of the spring seat.

What I claim as new, and of my invention and desire to secure by Letters Patent, is:—

1. In a spring platform, seats for the springs, and frames having mid portions D⁵, inclined portions D², one end of the frame provided with a hooking device, substantially as and for the purposes specified.
2. In a spring platform, seats for the springs, and frames having sides D², and middle portions D⁵, and end portion D⁷, and end hook at the other end, substantially as and for the purposes specified.
3. In a spring platform, seats for the springs, and frames connected to the seats, each made of a single rod bent so as to have mid-portions D⁵, inclined portions D², an end portion D⁷, the ends of the rod being approximated, and bent forming the hook D⁴, substantially as and for the purposes specified.
4. In a spring platform, and as an element of connection, frames each made of a single rod bent so as to have mid-portions D⁵, inclined portions D², end portion D⁷, and opposite end where the rods approximate provided

- with the hook D⁴, substantially as and for the purposes specified.
5. In a spring platform, and as an element of connection, frames each made of a single rod bent so as to have 5 mid-portions D⁵, inclined portions D², end portion D⁷, and opposite end where the rods approximate provided with the hook D⁴, the hook of one frame engaging the end D⁷ of an adjacent frame, substantially as and for the purposes specified.
10. 6. In a spring platform, as a new article of manufacture, a seat for a spring, consisting of a plate having a raised central portion bounded by depressed channel portion, an eye formed in the channel at a given point by raising the bottom of the channel, the adjacent portion 15 of the spring adapted to rest in the channel and to pass through this eye; and means for securing this seat to other portions of the platform, substantially as and for the purposes specified.
7. In a spring platform, as a new article of manufacture, 20 a seat for a spring, consisting of a plate having a raised central portion bounded by depressed channel portion, eyes formed in the channel at given points by raising the bottom of the channel, the adjacent portion of the spring adapted to rest in the channel and to pass through these 25 eyes, and means for securing this seat to other portions of the platform, substantially as and for the purposes specified.
8. In a spring platform, as a new article of manufacture, a seat for a spring, consisting of a plate having a raised central portion, bounded by a depressed channel portion, in turn bounded by a raised portion, an eye formed in the channel at a given point, by raising the bottom of the channel, the adjacent portion of the spring adapted to rest in the channel and to pass through this 35 eye, and means for securing this seat to other portions of the platform, substantially as and for the purposes specified.
9. In a spring platform, as a new article of manufacture, a seat for a spring, consisting of a plate having a raised central portion, bounded by a depressed channel portion, in turn bounded by a raised portion, the eyes formed in the channel at given points by raising the bottom of the channel, the adjacent portion of the spring adapted to rest in the channel and to pass through these 45 eyes, and means for securing this seat to other portions of the platform, substantially as and for the purposes specified.
10. In a spring platform, as a new article of manufacture, a seat for a spring, consisting of a plate having a channel provided with opening formed by raising the bottom of the channel, the adjacent end portion of the spring adapted to rest in the channel and to pass within this opening, and the ends curved over into the hook portions, substantially as and for the purposes specified.
55. 11. In a spring platform, as a new article of manufacture, a seat for a spring, consisting of a plate having a channel provided with two openings formed by raising the bottom of the channel, the adjacent end portion of the spring adapted to rest in the channel and to pass within these openings, and the ends of the plates formed into hooks, substantially as and for the purposes specified.
60. 12. In a spring platform, as a new article of manufacture, a seat for a spring, consisting of a plate having a channel provided with opening formed by raising the bottom of the channel, the adjacent end portion of the spring adapted to rest in the channel and to pass within this opening, and the ends curved over into the hook portions, and the frame D, one of whose sides is engaged by a hook of the seat, substantially as and for the purposes specified.
70. 13. In a spring platform, seats for the spring, the coiled inverted conical truncated springs, whose apexes respectively rest upon these seats, and are secured thereto, each seat provided with curved ends, a link pivoted at one end to a plate of the frame, and at the other end pivoted to a curved end of the spring seat, substantially as and for the purposes specified.
14. In a spring platform, seats for the springs, having the channel openings for the end of the springs formed by raising the bottoms of the channels, and having the curved end hooks, and the links F pivotally connected to the 80 frame, and engaging the adjacent hooks of these seats, substantially as and for the purposes specified.
15. In a spring platform, the combination of the springs and their seats, and the rod having a portion D⁵, and at each end of this portion an inclined portion D², each inclined portion connected to a spring seat, and a pivotal holder H², H⁵, H⁶, pivotally engaging the midportion D⁵ of the said rod, substantially as and for the purposes specified.
16. In a spring platform, the combination of the springs and their seats, and the rod having a portion D⁵, and at each end of this portion an inclined portion D², each inclined portion connected to a spring seat, and a pivotal holder H², H⁵, H⁶, pivotally engaging the midportion D⁵ of the said rod and the link F, pivotally connected to the 95 frame at one end and to the spring seat on the side opposite where said rod engages the latter, substantially as and for the purposes specified.
17. In a spring platform, the combination of the spring seats having curved ends, rod frames having sides D², and mid-sides D⁵ and end portions, these rod frames connected at their mid-sides to the spring seats, and at their end portions to each other, and the links F, connecting the spring seats to the sides of the frame, and the fixed holders H⁶, connecting the rod frames to the front of this frame, 100 substantially as and for the purposes specified.
18. In a spring platform, the combination of the spring seats, rod frames having sides D², midsides D⁵ and end portions, these rod frames connected at their midsides to the spring seats, and the end extension link devices, having 110 a straight end I³, pivotally connected to the frame, and having converging sides I², I⁵, provided at their meeting ends with hooks I, engaging an end portion of the said rod frame, substantially as and for the purposes specified.
19. In a spring platform, the combination of the spring seats having curved ends, rod frames having sides D², and midsides D⁵ and end portions, these rod frames connected at their mid-sides to the spring seats, and at their end portions to each other, and the links F, connecting the spring seats to the sides of the frame, and the fixed holders H⁶, connecting the rod frames to the front of this frame, and the end extension link devices, having a straight end I³, pivotally connected to the frame and having converging sides I², I⁵, and where these sides meet connected to an 115 end of the said rod frame, substantially as and for the purposes specified.
20. In a spring platform, the springs, and a rod frame made of one piece and bent substantially as shown, its free ends located together and formed with a hook K⁵, its mid-sides having the clamps K⁷ curved as shown and 120 adapted to engage the parts of adjacent springs, and the connecting pieces L², L⁵, one set connected to one end of the rod frame K, and the other set to the other end of this rod frame, the other ends of said connecting pieces being respectively connected to adjacent springs, substantially 125 as and for the purposes specified.
21. In a spring platform, springs, rod frames K, having side clamps engaging springs, and ends, and the converging connecting pieces L², L⁵, one set in one piece and hooked at its converged end to the end of the rod frame, 130 by a hook on the latter, and the other set of two pieces, each having at each end a hook, the converging ends hooked onto the end of the rod frame, and the other ends respectively to springs, and connections to the upper frame of the platform, substantially as and for the purposes 135 specified.
- In testimony whereof, I have hereunto set my hand, in the presence of two subscribing witnesses.
